UNITED STATES PATENT OFFICE.

ABRAHAM SHERMAN, OF BROOKLYN, NEW YORK.

DESIGN FOR A HANDBAG FRAME.

Application filed September 4, 1928. Serial No. 28,037. Term of patent 3½ years

To all whom it may concern:

Be it known that I, ABRAHAM SHERMAN, a citizen of the United States, residing in Brooklyn, New York, have invented a new, original, and ornamental Design for Handbag Frames, of which the following is a specification, reference being had to the accompanying drawing, forming part thereof, in which—

Fig. 1, represents a front view of a handbag frame.

Fig. 2, represents a plan view of a handbag frame.

Fig. 3, represents a side view of a handbag frame.

I claim—

The ornamental design in a handbag frame as shown.

ABRAHAM SHERMAN.
